UNITED STATES PATENT OFFICE.

JOSEF A. GNOSS, OF SCRANTON, PENNSYLVANIA.

FIGURE-WEAVING ATTACHMENT FOR DOBBY-LOOMS.

No. 846,198.

Specification of Letters Patent.

Patented March 5, 1907.

Application filed September 6, 1905. Serial No. 277,229.

To all whom it may concern:

Be it known that I, JOSEF A. GNOSS, a citizen of the United States, residing at Scranton, in the county of Lackawanna and State of Pennsylvania, have invented certain new and useful Improvements in Figure-Weaving Attachments for Dobby-Looms, of which the following is a specification.

My invention relates to the shed-forming mechanism of looms, and more particularly, to means for weaving what are known as "warp" effects, where the figure formed by the warp-threads is designed to come again into the same longitudinal position in the fabric only after two or more repeats of the figure have been formed on different transverse lines. Heretofore these warp effects have required a Jacquard loom and its accompanying cards in order to produce them; and the object of my invention is to provide means whereby an ordinary dobby-loom—such as the Knowles-Crompton loom, shown in general principle in Patent No. 666,787, of January 1, 1901—may do the work, which it has not been adapted to do heretofore.

My invention consists in means whereby a certain set or series of threads may be held in the upper shed of the loom, while the threads of another section or sections are being woven to form a figure.

Heretofore dobby-looms have not been adapted to weaving figures formed by warp or floating threads, unless the figures were in transverse alinement each with the other. Patterns arranged as shown in Fig. 7 could not be woven on the ordinary dobby-loom, for the reason that during all the time one set or series of figures is being woven the threads of other sets require to be held out of the way in the upper shed. The figure-hooks or harness-levers of a dobby-loom being each connected to a certain thread of each longitudinal line of figures, it follows that the raising of that lever would mean the lifting of all threads connected therewith without distinction clear across the entire width of the fabric. It would be theoretically possible to operate only a series of threads at a time and raise the others out of the way by doubling, tripling, or quadrupling the number of dobby-levers, increasing the width of the pattern-chain to correspond; but such a construction would be impracticable, as it would necessitate the use of too many heddle-frames and add to the complication of the mechanism enormously. It

would require also a change in the dobby-loom now on the market, and it is to be understood that one of the objects of my invention is to adapt the ordinary dobby-loom of 60 say, twenty hooks, to the weaving of these warp effects without adding to the complication or changing in any manner the mechanism hereof.

In the accompanying drawings I have 65 shown my invention as applied to an ordinary dobby-loom of the Knowles-Crompton type, and therein—

Figure 1 is a rear view of the upper part of a loom above the reed. Fig. 2 is a longitudinal view, partly in section on an enlarged scale, of one of the section-frames. Fig. 3 is a plan thereof. Fig. 4 is a cross-section on line $x-x$ of Fig. 3. Fig. 5 is a diagrammatic side view of the ground-warp and floating-warp threads and the section-frame connections. Fig. 6 is a diagram illustrating the action of the section-frames. Fig. 7 is a plan of a pattern such as is designed to be woven on dobby-looms by the use of my invention.

As my invention has nothing to do with the shuttle mechanism, driving-gears, &c., and as these are well known in the art, I have omitted them in several views.

In all the figures like numerals designate like parts.

In the drawing, 2 designates the loom-frame, having upon its top the usual sets of sheaves 2', over which pass the usual harness-cords to the heddles or harness-frames 2'', which operate the warp-threads which form the ground of the fabric. These heddles may be connected to any of the ordinary forms of ground-harness.

3 designates the harness or dobby levers. These harness-levers are operated by any of the ordinary arrangements of raising and depressing jacks and knives, such as are shown in patent to Wyman, No. 666,787, of January 29, 1901, and embodied in the Knowles-Crompton loom, the jacks in turn being actuated by the pins 4 4' of the pattern-chains 5 5'. The harness or dobby lever actuating mechanism being well known and not a part 105 of my invention, I have not illustrated the same in detail.

6 are upright standards fast on the upper bars of the loom-frame, and 6' are upwardly-inclined supports whose lower ends are attached to the lower frame and whose upper ends are supported in the upper ends of the

uprights 6 in any desired manner. Between the supports 6' extend transverse rods 6", preferably of glass; over which pass the neck-cords which connect the warp-threads with the harness-levers 3.

Supported rigidly within the frame of the loom are the four upright guide-rod 7. Two of the rods are at opposite ends of the rear frame-bar and two at the opposite ends of the front frame-bar. Mounted to slide up and down on these guide-rod are the rectangular section-frames I II III, whose use and construction form the principal feature of my invention.

15 As shown in Figs. 2, 3, and 4, each frame preferably consists of two longitudinal sides 8 and two end pieces 9. Each frame has at its ends the eyes 10, which pass over and slide upon the guide-rod 7. The inside face of the side pieces are grooved, as seen in the section, Fig. 4, for the reception of the comber-slips 11. To hold the comber-slips in place, I provide the side pieces with vertical holes 10', through which enter pins 10", which 20 pass through holes in that portion of a comber-slip which is inserted into the groove 10. It will thus be seen that any number of comber-slips desired may be used and that they may be adjusted to any position along 25 the frame necessitated by the pattern.

The section-frames are each about thirty-six inches long by four inches wide. There are as many of these frames as there are longitudinal figure-lines before a repeat. I have shown in Fig. 7 a pattern having three lines of laterally-displaced figures before a longitudinal repeat, and I have therefore shown three section-frames I II III in the illustrations. These are arranged one above 30 another in vertical alinement, and each controls the neck-cords to one series of transverse lines of figures. Through each comber-slip of the three section-frames pass the neck-cords of each longitudinal line of warp-threads. This will be clear from the diagram, Fig. 6. In this case I have shown only three sets or transverse lines of figures or figures shifted in position three times before the first set is repeated, and for simplicity I have shown each figure as being formed by four warp or floating threads. There would be, therefore, four figure-levers in the dobby. From each lever would run as 35 many neck-cords for raising the floating threads as there were longitudinal lines of figures in the pattern. The neck-cord for each lever would pass through its proper hole in one of the comber-slips. Thus every comber-slip in each section-frame would have passing through it a neck-cord from each one of the levers. Now it is obvious that a lift of any lever would pull on all the neck-cords attached thereto and leave that particular thread in every one of the longitudinal lines of floating threads; but in order 40

to prevent any lever from operating any but one set of threads at a time I connect the neck-cords to the section-frames as follows: No. I frame controls the neck-cord for the No. I line of figures, and it is provided with comber-slips which correspond with such lines.

Through each of these comber-slips the neck-cords from each harness-lever pass to those warp-threads which are to form the No. I line of figures. All these threads are knotted or otherwise formed with a protuberance which is too large to pass through the holes in the comber-slip of section-frame I. No. II frame controls the lifting of the neck-cords for the No. II line of figures, and its comber-slips are placed to correspond with such line—that is, to one side of the comber-slips of No. I frame or, in the case shown, at one-third of the distance between the comber-slips of No. I frame. The neck-cords to the threads that are to form the No. II line of figures pass down through the No. I frame between the comber-slips thereof and through the holes in the comber-slips of the No. II frame, being knotted above the comber-slips, as above described. The neck-cords to the threads of the No. III line of figures pass down between the comber-slips of the Nos. I and II frames and through the holes in the comber-slips of the No. III frame, being knotted above them in the same manner as herefore described. The effect of lifting these neck-cords is to slacken them above the comber-slips to such degree that as they are not taut the dobby-levers do not operate on them to lift that portion of each neck-cord below the raised section-frames.

If two of the frames are lifted and the other left down, then the dobby-levers will only operate on those sets of warp-threads which pass through the mails of those neck-cords which are not lifted. The result will be that the sets of threads last referred to will be woven into a figure and the other two sets will be raised into the upper shed and remain there as floating threads until their respective frames are lowered and they in their turn are worked into the pattern.

In order to limit and regulate the amount of vertical movement of the section-frames, I provide the rods 7 with stops 7', which may be attached thereto by set-screws, as shown. If there are three section-frames, there will be two stops on each rod, dividing the height of the rod into three spaces, in each of which a section-frame plays. It is to be understood that there are as many spaces as there are section-frames, each space to be sufficient to allow its section-frame to lift sufficiently to raise its particular set of pattern-threads into the upper 130

shed when the frame is at the upper extremity of its movement.

In order to lift the frames, I carry harness-cards from the ends of each one over the sheaves 2' or, if desired, over the bars 6" of the inclined frame 6' to one of the levers of the dobby. If there are three frames, I use three of the dobby-levers or as many levers as there are frames. When one of these levers is moved, it raises the connected section-frame and holds it raised until the section-frame pattern-pins allow it to be lowered.

The harness-levers for the body fabric, as before stated, may be operated by the ordinary pattern-chain mechanism, whose chain itself is as broad as and operates the entire range of dobby-levers. As this, however, would necessitate that the pins for the section-frame levers be repeated three times over in the length of the chain, I prefer to make the figure-lever and heddle-lifting pattern-chain 4' separate from the section-frame chain 4" and have it bear a relation to the section-frame chain, as one to two, one to three, and one to four, depending upon whether the pattern requires two, three, or four section frames. In the figures I have shown three section-frames, and the pattern-chain 4' is therefore one-third the length of the chain 4". Thus the figure-pattern chain completes its cycle three times during each revolution of the section-frame and heddle-actuating chain.

When the figure to be made is quite small, needing, say, only twenty picks for its formation, one chain will be all that is necessary; but if the figure is displaced in its position three times with thirty picks to the figure then the figure-chain must have ninety pins. With the double chain, however, the figure-chain has only thirty figure-pins to be set, and the chain which operates the section-frames has ninety pins. As it is the setting of the figure-pins which is difficult, I save the labor necessary to set sixty figure-pins. Of course the larger the figure the larger the number of picks to it; the greater the number of levers used and the more times the figure is displaced the greater the saving of time in using separate figure and heddle and section frame chains. These chains used are exactly the same as those now used in dobby-loom, and except that they are made

in two longitudinal parts. Supposing the dobby to have twenty harness-levers and the figure requires fourteen levers to make it, fourteen of the levers will be connected to the neck-cords of the floating threads, one lever to No. I frame, one lever to No. II frame, one lever to No. III frame, two levers will be used for the ground-harness heddles, and one lever will be empty.

The operation of my invention will be plain from what has before been stated. Its

advantages are many. It obviates the use of a Jacquard loom with all its complications and the making of the cards therefor. It requires no change in the ordinary dobby-loom, and the frames can be attached thereto quite easily. The loom need not be reduced in speed, and, indeed, the invention is specially applicable for high-speed looms. The construction is exceedingly simple, cheaply made, and easily applied.

In addition to the above obvious advantages, it is to be noted that the space occupied by the figure neck-cords back of the heddles is only one and three-quarters inches deep. Heretofore while it has been possible to weave small figures not displaced it required the use of from twelve to twenty heddles, which took up from eight to fourteen inches. As stated above, the use of my invention takes up less than two inches of space behind the ground-heddles.

When it is desired to weave one line of figures and then raise the figure-threads into the upper shed while the ground is being woven, one section-frame may be used, engaging with all the figure-threads to hold them out of operation. By this means the length of chain and the number of pins having to be set thereon to actuate the figure-levers may be much reduced.

I do not wish to be limited to the exact form of "section-frame" I have shown, as by that term I include any form of frame or board through which the neck-cords can pass.

My invention is slight in cost, easily applied to any dobby-loom now on the market, reliable in its operation, and of great utility in figure-weaving.

Having described my invention, what I claim is—

1. In a loom, a set of neck-cords comprising the cords for actuating those warp-threads which are to form an entire figure, a vertically-movable frame engaging when lifted to raise each one of the set of neck-cords but allowing the said cords to have free vertical movement themselves independent of the frame, mechanism for lifting said frame at intervals to lift the neck-cords to slacken the same above the lifted frame, and mechanism for raising and lowering the neck-cords independently of the said frame to form a figure, substantially as described.

2. In a loom, a set of neck-cords comprising the cords for actuating those warp-threads which are to form an entire figure, a vertically-movable frame having a comber-board through the holes of which the neck-cords pass, stops on said cords above the comber-board incapable of passing through the holes of said board, mechanism for raising said frame at intervals to engage with said stops to raise the neck-cords and slacken the same above the lifted frame, and mechanism for

raising and lowering said neck-cords independently of the said frame to form a figure, substantially as described.

3. The combination in a loom of a plurality of vertically-movable section-frames, two or more series of sets of neck-cords each set comprising the cords for actuating the threads which are to form an entire figure and each attached to one of said section-frames and to no other frame, means for lifting said frames at intervals so as to slacken the attached cords above the lifted frame, and mechanism above said frames to which the neck-cords for all the frames are connected and by which said cords are raised and lowered at proper intervals to form a figure, substantially as described.

4. In a loom, one or more series of sets of neck-cords, each set comprising the cords for actuating the warp-threads which are to form an entire figure, and one or more vertically-movable frames, each frame engaging when lifted to raise one series of neck-cord sets and one series only, but allow the said cords to have free vertical movement themselves independently of the frames, means for lifting each of said frames at intervals to lift the series of neck-cords with which it engages to slacken the same above the lifted frame, and means by which the neck-cords are raised and lowered independently of the frames at intervals to form a figure, substantially as described.

5. In a loom, one or more series of sets of neck-cords, each set comprising the cords for actuating the warp-threads which are to form an entire figure, and one or more vertically-movable frames, each frame engaging when lifted to raise one series of neck-cord sets and one series only, but allow the said cords to have free vertical movement themselves independently of the frames, means for lifting each of said frames at intervals to lift the series of neck-cords with which it engages to slacken the same above the lifted frame, figure-hooks above said frames to which the neck-cords of all the frames are attached and by which the neck-cords are raised and lowered independent of the frames, and mechanism for actuating the said hooks at intervals to raise one or more of the neck-cords of each set to form a figure, substantially as described.

6. In a loom, a series of heddles for raising and lowering the warp-threads for the ground of the fabric to be woven, two or more series of sets of neck-cords, each set comprising the cords for actuating the threads which are to form an entire figure, two or more vertically-movable frames, each frame engaging to raise one series of neck-cord sets and one series only, when it is raised but allowing the cords of a set to have free vertical movement independently of the frames, mechanism for lifting and lowering said ground-warp hed-

dles when the frames are lowered, mechanism for lifting each of said frames at intervals to lift the series of sets of neck-cords with which it engages in order to slacken the same above the lifted frame, and mechanism whereby the single neck-cords are raised and lowered independently of the frame at intervals to form a figure, substantially as described.

7. In a loom, two or more series of sets of neck-cords each set comprising the cords for actuating those warp-threads which are to form an entire figure, a plurality of vertically-movable frames one above another each frame having comber boards or slips therein through which neck-cords of all sets pass, stops on the neck-cords, stops on each neck-cord of a set of neck-cords above the comber-boards of one or another of the frames adapted to be engaged by the comber-board when its respective frame is raised, mechanism for lifting each of the frames at intervals to bear against the neck-cord stock above it to lift the said cords and slacken them above the lifted frame, and mechanism by which the said neck-cords are raised and lowered independent of the frames to form a figure, substantially as described.

8. In a loom, a plurality of vertically-movable section-frames one above another in the same plane, comber boards or slips in each frame spaced apart from each other, comber boards or slips of one frame being out of vertical alignment with the comber boards or slips of every other frame, two or more series of sets of neck-cords each set comprising the cords for actuating those warp-threads which are to form an entire figure, the cords of each set passing through the holes of a comber slip or board in one frame and through the spaces between the comber-slips of the other frames, a stop on each neck-cord above the comber-boards through which it passes and adapted to be engaged by the comber-board when its frame is lifted, mechanism for lifting each of the frames at intervals to bear against the neck-cords and slacken them above the lifted frame, and mechanism by which the said neck-cords are raised and lowered independently of the frame to form a figure, substantially as described.

9. In a loom, two or more series of sets of neck-cords each set comprising the cords for actuating those warp-threads which are to form an entire figure, vertical guide mounted on the loom, two or more vertically-movable frames sliding on said guide-bars and mounted one above another, stops on said guides for limiting the vertical movement of said frames, comber boards or slips in said frames through the holes of which the neck-cords of all the sets of neck-cords pass, stops on each of the neck-cords of a set above the comber-boards of one or another of the frames and

adapted to be engaged by the same when its respective frame is raised, mechanism for lifting each of the frames at intervals to bear against the neck-cord stops above it to lift the said cords and slacken them above the lifted frame, and mechanism by which the neck-cords are raised and lowered independently of the frames to form a figure, substantially as described.

10. In a dobby-loom, one or more series of sets of neck-cords each set comprising the cords for actuating those warp-threads which are to form an entire figure, a plurality of vertically-movable frames one above another, each frame having comber boards or slips therein through which the neck-cords of all the sets of neck-cords pass, stops on each neck-cord of a set above the comber-boards of one or another of the frames and adapted to be engaged by the same when its respective frame is raised, a plurality of figure-levers above the said frames, each lever connected with one of the neck-cords to each set to raise or lower the same to form a figure, two or more levers connected each to one of the section-frames to raise or lower the same at proper intervals, and two or more levers attached to heddles for raising or lowering the threads of the ground-warp, substantially as described.

11. In a dobby-loom, one or more series of sets of neck-cords each set comprising the cords for actuating those warp-threads which are to form an entire figure, a plurality of vertically-movable frames one above another, each frame having comber boards or slips therein through which the neck-cords of all the sets of neck-cords pass, stops on each neck-cord of a set above the comber-boards of one or another of the frames and adapted to be engaged by the same when its respective frame is raised, a plurality of figure-levers above the said frames, each lever connected with one of the neck-cords of each set to raise or lower the same to form a figure, an inclined frame mounted upon the loom and having transverse rods over which the neck-cords pass from the said figure-levers down and through the said frames, two or more levers connected each to one of the section-

frames to raise or lower the same at proper intervals, and two or more levers attached to heddles for raising or lowering the threads of the ground-warp, substantially as described.

55

12. An attachment for looms comprising guide-rods, a rectangular frame provided with guide-eyes at the ends surrounding said rods and adapted to slide up and down thereon, said frame being formed of two end pieces and two longitudinal pieces, the latter grooved along their length and provided with perforated comber-slips, the perforations therein adapted to engage with the harness-cords of a loom, and the ends of said comber-slips fitting in the side grooves in the side pieces, and pins whereby the said comber-slips may be held adjusted at any desired point.

13. In a loom, one or more series of sets of neck-cords each set comprising the cords for actuating the warp-threads which are to form an entire figure, a plurality of vertically-movable frames, each frame engaging when lifted to raise one series of neck-cord sets and one series only, but allowing the said cords to have free vertical movement themselves independently of the frames, harness-levers, one for each of said frames to lift the same at intervals to lift the series of neck-cords with which it engages to slacken the same above the lifted frame, figure harness-levers above said frames to each of which one of the neck-cords from each set is attached and by which one of the neck-cords of each set is raised and lowered independently of the frames, and a double lever-actuating chain, one chain actuating the figure-levers and the other chain actuating the said frame-raising levers, substantially as described.

In testimony whereof I have signed my name to this specification, in the presence of two subscribing witnesses, this 23d day of August, 1905.

JOSEF A. GNOSS.
